(57) **CLAIM**

The ornamental design for a slanted power plug head, as shown and described.

DESCRIPTION

FIG. 1 is a front perspective view of a slanted power plug head, showing our new design;

FIG. 2 is a back perspective view thereof;

FIG. 3 is a side view thereof;

FIG. 4 is a top view thereof;

FIG. 5 is a front view thereof; and,

FIG. 6 is a back view thereof.

The broken lines in the drawings illustrate environmental subject matter that forms no part of the claimed design.

1 Claim, 6 Drawing Sheets(56)
